PORTABLE DICTATING MACHINE

Harry M. Billings, 546 Bryant St.,
San Francisco, Calif. 94107

Filed Nov. 20, 1967, Ser. No. 9,472

Term of patent 3½ years

(Cl. D26—14)

FIG. 1 is a front perspective view of a portable dictating machine showing my new design.

FIG. 2 is a left side view of the dictating machine shown in FIG. 1.

FIG. 3 is a back view of the dictating machine shown in FIG. 1.

The dominant features of my design reside in the portions shown in full lines on the drawing.

I claim:

The ornamental design for a portable dictating machine, as shown and described.
